UNITED STATES PATENT OFFICE

JOSEPH C. HIGGINS, OF CHICAGO, ILLINOIS

WINDOW STRUCTURE

Application filed May 29, 1929. Serial No. 366,818.

This invention relates to windows, and more particularly to a structure to be used for cellars, basements, and the like.

The principal object of the invention is to produce an improved all-metal structure which is simple and inexpensive, yet durable and weather-proof; to provide for the ready removal of the sash from the window frame and its replacement therein, at will; to provide for pivotally supporting the sash at its lower edge portion upon the window frame so that it may be tilted to open position; and to attain certain other advantages as will hereinafter more fully appear.

5 The invention consists in the novel construction and in the parts and combinations and arrangements of parts as hereinafter described and set forth in the appended claims.

In the accompanying drawings illustrating practical embodiments of the invention,

Fig. 1 is a front elevation of a window frame and sash, looking at the inner side thereof, the sash being shown in closed position;

5 Fig. 2 is a similar view looking at the outer side of the frame and sash;

Fig. 3 is a perspective view showing fragmentary cooperating corner portions of the sash and frame;

0 Fig. 4 is a fragmentary section showing the sash as supported in its tilted position on the frame;

Fig. 5 is an outer side elevation of a modification of the window structure;

5 Fig. 6 is a section on the line 6—6 of Fig. 5;

Fig. 7 is an outer side elevation of the sash detached from the frame;

Fig. 8 is a section on the line 8—8 of Fig. 7;

Fig. 9 is a fragmentary view, in inner side elevation, of the corner portion of the sash;

Fig. 10 is a similar view of the opposite corner portion of the frame; and

Fig. 11 is a fragmentary section on the line 11—11 of Fig. 5.

5 The preferred embodiment of the invention, as illustrated in the accompanying drawings, comprises an all-metal window frame including top and bottom members 12 and 13, respectively, and end members 14, said members being of angle iron section. These mem-

bers 12, 13 and 14 are rigidly connected at their corners by welding or other suitable means of attachment, and the top member 12 and end members 14 have secured thereto, as by riveting or welding, angle members 15 and 16, respectively, said combined sections producing in effect a substantially Z-bar section. Secured on the lower frame member 13 is an angle member 17 which produces in effect a T-bar section.

By the arrangement of the structural parts as shown in the drawings and as above described, the frame is provided with an in-turned flange 18 extending across the outer edges of its rail 12 and end rails 14, the same providing an effective guard for preventing the entrance of dust or water, as well as an abutment for the sash in the closed position of the latter. The upstanding flange 19 of the angle member 17 is disposed on the inner side of the frame and forms a support on which the sash is adapted to pivot, as will be presently described, and also serves to prevent the entrance of dust or water.

5 The sash, designated generally by the reference numeral 20, comprises a rectangular frame whose top and bottom members 21 and 22, respectively, and end members 23 are of angle iron section and rigidly connected at the corners of the frame by welding or other suitable means. Preferably, the upper and lower sash members 21 and 22 are connected by the intermediate bars 24 which are of T-iron section, thereby dividing the window into three separate panels in which the panes 25 are mounted. On the lower member 22 of the sash an angle member 26 is rigidly secured, the depending flange portion 27 of said member 26 affording a guard for preventing the entrance of dust or water at the bottom of the sash, as will presently more fully appear.

On the inner face of the sash and near its lower corners plates 28 are firmly secured by riveting or otherwise, the lower edge portions 29 of said plates 28 resting upon the adjacent marginal portions 30 of the upstanding flange 19 at the inner side of the lower or sill member 13 of the window frame, when the sash is placed in the frame.

The lower portions of the end flanges 18 of the frame are cut away or notched, as at 31, affording a corresponding shoulder 32 at each end of the frame, said shoulders being 5 preferably beveled, as at 33. The shoulders are engaged by the adjacent end portions 34 of the flange 27 on the sash when the sash is tilted on its supporting plates 28 which rest on the adjacent edge portions of the flange 19 10 of the frame.

10 The end portions 34 of the flange 27 on the sash are cut away just sufficiently to fit freely between the notched portions 31 of the end flanges 18 of the frame when the sash is placed 15 in the frame. In the closed position of the sash its lower angle member 22 enters the frame behind the upstanding flange 19 thereof, and the lower marginal portion of the flange 27 on the sash overhangs the outer 20 marginal portion 35 of the horizontal flange of the angle member 17 on the lower frame member 13, thus producing an effective baffle for checking a draft and preventing the entrance of dust or water at the lower portion 25 of the sash.

In the modification illustrated in Figs. 5 to 11, inclusive, the structure is very similar to that hereinbefore described. One notable difference is that the frame is more nearly 20 a perfect square, instead of an oblong, and it has but a single panel. Instead of merely notching the flange 18 of the frame, as at 31 in Fig. 3, a lug or extension 36 is provided, whose lower edge portion affords a shoulder 25 32', which in effect, is identically the same as the shoulder 32 hereinbefore described. In both modifications it is preferable to extend the side marginal portions 37 of the plates 28 some distance beyond the adjacent end portions 30 of the flange 19 which supports them, should there be an undue 30 amount of play between the cooperating rear portions of the sash and frame, and, as a 35 matter of fact, there should be considerable clearance between the outer side of the sash and the flange 18 of the frame when the sash is closed, as indicated as at 38 in Fig. 11, this 40 clearance being obviously necessary to permit an easy pivotal action of the sash.

45 In accordance with the present invention, a practical and durable window structure is produced which may be used to considerable 50 advantage in cellars or basements of buildings, or in any other place where it is desirable to have provision for readily opening the sash for ventilating purposes, or for removing the sash entirely from frame to prevent breakage 55 thereof when it is desired to use the win-

dow opening for the passage of coal or other heavy or bulky material therethrough.

Obviously, the structure admits of considerable modification without departing from the spirit and scope of the invention as defined by the appended claims. Therefore, the invention is not limited to the specific construction and arrangements shown in the accompanying drawings.

Having thus described my invention, what I claim as new and desire to secure by Letters Patent is:

1. A window structure comprising a metal frame, the top and end members of said frame being substantially Z-shaped in cross section, and the bottom member of said frame being substantially T-shaped in cross section, said top and end frame members having inturned flanges at the outer side of the frame, and said bottom member having an upstanding flange at the inner side of the frame, a sash comprising angular top, bottom and end frame members, the bottom member of said sash frame having a supplemental angle member thereon providing a depending flange at its outer side, lugs on said sash for removably supporting it on the upstanding flange portion of the bottom member of the window frame proper, said frame member proper having a shoulder for the engagement of the adjacent lower portion of the sash for supporting said sash in tilted position.

2. A window structure comprising a frame having an upstanding flange at the inner marginal portion of its bottom member, and a sash detachably mounted in said frame, said sash comprising an angular bottom member having provision on the inner face of its lower portion for detachably and pivotally supporting it on said upstanding flange of the lower member of the frame, in closed position the lower portion of the sash overlapping and being close to said upstanding flange and having a depending outer marginal flange overhanging the outer edge of said bottom member of the frame.

3. A window structure comprising a metal frame and sash having an upstanding inner marginal flange of its bottom member of the frame affording a weather guard and support for the lower portion of the sash, said sash being shouldered on its inner face for detachably and pivotally supporting it on said upstanding flange of the bottom frame member and having a depending outer marginal flange overhanging the outer edge of said bottom frame member and constituting a supplemental outer weather guard, the adjacent end portions of said depending flange of the sash and outer marginal flanges of the side members of the frame being provided with interengaging shoulder portions for supporting the sash in tilted open position.

4. A window structure comprising a frame having an upstanding flange at the inner side

of its bottom member, and a sash movable in and detachable from said frame, said sash having a shoulder on its inner face pivotally supported on said upstanding flange of the bottom member of the frame and having a laterally projecting portion overlapping the inner face of the adjacent portion of the frame whereby, in the closed position of said sash, the sash is prevented from moving outward, the lower portion of the sash being engaged behind the outer face of said upstanding flange of the bottom member of the frame so as to prevent inward movement of the sash, whereby the sash is normally maintained in its pivotally supported relation to the frame, and a depending flange at the outer edge of the lower portion of said sash overhanging the outer edge of the bottom frame member affording a weather guard.

In testimony whereof I have signed my name to this specification.

JOSEPH C. HIGGINS.
